(57) **CLAIM**

The ornamental design for the combination glasses, as shown.

DESCRIPTION

FIG. 1 is a top view of the invention.

FIG. 2 is a front view of the invention.

FIG. 3 is a side view of the invention. The other side view is symmetrical.

FIG. 4 is a back view of the invention.

FIG. 5 is a bottom view of the invention.

FIG. 6 is a taken along line 6—6 of FIG. 1.

FIG. 7 is a top view of the invention.

FIG. 8 is a front view of the invention.

FIG. 9 is a side view of the invention. The other side view is symmetrical.

FIG. 10 is a back view of the invention.

FIG. 11 is a bottom view of the invention; and,

FIG. 12 is a taken along line 12—12 of the FIG. 7.
